ELEVATOR SYSTEM

Edgar M. Bouton, Nutley, and Danilo Santini, Tenafly, N. J., assignors, by mesne assignments, to Westinghouse Electric & Manufacturing Company, East Pittsburgh, Pa., a corporation of Pennsylvania

Application July 4, 1942, Serial No. 449,716

14 Claims. (Cl. 187—29)

Our invention relates to systems of control for electric elevators and more particularly to such systems as include a number of elevator cars, operating together as a bank, and are controlled by passenger-operated push buttons located at the various floor landings.

Although not limited thereto, our invention is particularly applicable to elevator systems in which the elevator cars are driven at relatively high speeds by variable-voltage or other high-speed motive equipment and are automatically stopped at the floors by automatic landing equipment or equivalent apparatus. Such elevator systems provide a particularly efficient passenger service available for office buildings and other tall structures having a large number of floors and a relatively large volume of passenger traffic.

In such systems, in the absence of special control provisions which will be described, there is a tendency for the various cars to distribute the building traffic unevenly, and, in the taller buildings, for the cars to become "bunched" and thus prevent reasonable uniformity of spacing between them.

These systems also tend to provide better service at certain floors than at others, particularly during the noon and evening rush periods, at which times a relatively large number of calls are registered at practically all floors of the building within a relatively short period of time. At such rush periods, each car is filled to capacity by a relatively few stops, perhaps three or four. Considering a car leaving the upper terminals, such a car is usually required to make these few stops at the upper floors and so passes the lower floors without stopping. Because of the frequency with which calls are registered, the next car of the series is also filled to capacity by three or four stops at upper floors and so passes the lower floors without stopping. In the operation of these systems, therefore, the response to calls registered from lower floors of the building is delayed until most of the traffic from the upper floors has received attention.

In order to provide more uniform service throughout the building during heavy traffic peaks, we have devised a selective system for operating the elevators in which a car may be reversed automatically in any part of its shaft travel if conditions exist which require its reversal for the best service. An up traveling car with passengers should not be reversed until the passengers have been discharged, and a car should not be reversed unless there is sufficient demand at the lower floors of the building to require practically its full capacity. Otherwise the service in some other portion of the building may suffer.

Our system will provide normal service to the entire building as long as the demands on the system are normal. In this normal service each car runs to the highest call before reversing. In the evening when the building is being emptied, this highest call will usually be a down floor call.

As the demand for service becomes heavier, the upper floors of the building will tend to monopolize it and the lower floors will not receive sufficient service. When this condition occurs, the number of calls registered at the lower floors will increase. When these have reached a predetermined number, one of the cars will reverse at the highest down call occurring in a "lower zone" which comprises a selected number of the lower floors of the building, and it will serve these lower floors at the expense of the service at the upper floors. By a proper choice of division between upper and lower floors and by requiring certain of the cars to travel to the highest down call of the upper floors by making it incapable of lower zone reversal, a balance can be obtained where all floors will receive substantially equal service.

It is, therefore, an object of our invention to provide a novel elevator system for equalizing the service rendered to the floors, particularly during a period of high service demand.

A further object is to provide means for rendering service to the lower portion of the floors served by a bank of elevators without making an arbitrary division served by certain cars regardless of the requirements.

It is also an object to provide a system in which certain selected cars will normally make complete round trips in operating and other selected cars may not normally make complete round trips to the upper terminal but will under certain conditions operate to answer only down calls at lower floors, without being limited to a particular number of lower floors, regardless of the fact that the system is divided into an upper zone of a selected number of upper floors and a low zone of a selected number of lower floors. In other words, it is an object to divide the system into an upper group of floors and a lower group of floors and to also divide the cars into two groups, one group answering calls throughout the system and the other group normally answering only calls in the lower group of floors but going above the lower floors when the number of calls in the lower floors is below a predetermined minimum.

Other objects of our invention will become evident from the following detailed description taken in conjunction with the accompanying drawings, of which:

Figure 1 is a diagrammatic representation of an elevator system embodying our invention;

Fig. 2 is a diagrammatic representation of the stationary contact segments and the moving brushes on a floor selector for one of the elevator cars embodied in Fig. 1, with the brushes disposed in the position they take when the car is stopped at the third floor;

Figs. 3, 4, 5 and 6 collectively constitute a diagrammatic representation in straight-line style of the circuit connections for the two-car elevator system illustrated in Fig. 1. The figures should be assembled vertically in numerical order with Fig. 3 at the top.

Figs. 3A to 6A, inclusive, are key representations of the relays in Figs. 3 to 6, inclusive, illustrating the coils and contact members disposed in horizontal alignment with their positions in the straight-line circuits of Figs. 3 to 6. Figs. 3A to 6A should be placed beside the corresponding Figs. 3 to 6 to facilitate the location of the various coils and contacts.

The elevator system illustrated is provided with two cars A and B for serving seven floors. This number of cars and this number of floors have been selected for the purpose of simplifying the disclosure as much as possible, but it is to be understood that the invention may be used for any reasonable number of cars in a bank serving any reasonable number of floors. For example, the invention would be suitable for an installation of six cars serving thirty floors.

For the sake of simplicity, the apparatus individual to each car will be given the same reference characters except that the apparatus for car B will be given the prefix B to indicate that it is for car B instead of for car A.

Apparatus individual to car A

D—down switch
E—slow-down inductor relay
F—stopping inductor relay
G—inductor holding relay
H—high car call relay
J—high call reversing relay
K—high floor call relay
M—car running relay
P—inductor plates
R—resistors
S—floor call stopping relay
T—car call stopping relay
U—up direction switch
V—high speed relay
W—up direction preference relay
X—down direction preference relay
Y—quota adjusting relay
Z—limiting relay
TR—zone transfer relay
DR—door relay

Q—Quota relay

Attention is directed to the fact that some of the features illustrated and described in this ap-

plication are illustrated and described in the co-pending application of H. W. Williams, D. Santini and M. L. Mount, Serial No. 450,110, filed July 8, 1942, and assigned to the Westinghouse Electric Elevator Company.

Apparatus in Fig. 1 of the drawings

Referring more particularly to Fig. 1 of the drawings, it will be observed that car A is arranged to be supported in a hatchway by a cable 10 which passes over a sheave 11 to a counterweight 12. The sheave 11 is mounted for rotation by a shaft 13 driven by a motor 14. A brake 15 of the usual spring-operated, electro-magnetically-released type is provided for stopping further rotation of the sheave 11 when the motor 14 is deenergized.

A floor selector 16, of any suitable type, is provided for connecting the various electrical circuits of the system in accordance with the position of car A. The shaft 13 is extended to operate a brush carriage 17 on the floor selector 16 by mechanically rotating a screw-threaded shaft 18 on which the carriage is mounted. The carriage 17 is provided with a number of brushes which are disposed, upon movement of the car, to successively engage stationary contacts arranged in rows on the selector in position to correspond to the floors of the building. For simplicity, only two brushes, 32 and 42, and two rows of contact segments, b2 and g2, etc., disposed to be engaged by them are illustrated in Fig. 1, but it will be understood that in the system to be described herein, as well as in practice, a much larger number of brushes and rows of contact segments is required. Other forms of selectors may be substituted for the selector shown, if desired.

A starting switch CS is mounted in the car to be operated by the attendant to start the car. When the car switch is rotated anticlockwise, it closes its contacts CS1 to start the car for the direction for which it is conditioned to operate. When the car switch is centered, it leaves the control system of the car in such condition that the car can be stopped by operation of hall buttons at the floor landings or stop buttons in the car. It is to be understood that the car may be operated by the car switch or that any suitable control means may be substituted for the car switch. The illustration of the car switch is used for simplicity in describing the system.

The car buttons 2c, etc. (one for each floor) are mounted in the car, so that the attendant may, by operating them, cause the car to stop automatically at any floor. The direction of operation of the car is controlled by relays W and X as will be described in connection with Fig. 3.

The hall buttons are mounted at the floor landings, in order that waiting passengers may cause the cars to stop thereat. An up button and a down button are provided at each floor intermediate the terminals. A down button is disposed at the top terminal and an up button at the bottom terminal. Fig. 1 illustrates only the up call button 2U and the down hall call 2D for the second floor.

In order to automatically effect accurate stopping of car A at the floors in response to operation of the stopping buttons 2c, etc., in the car, or by operation of the hall call buttons 2U, 2D, etc., at the floors, a slow-down inductor relay E and a stopping inductor relay F are

mounted on the car in position to cooperate with suitable inductor plates of iron or other magnetic material, mounted in the hatchway adjacent to each floor. Only the up plates UEP and UFP and the down plates DEP and DFP for the second floor are illustrated. Similar plates are provided for each floor, except that the top terminal has only up plates and the bottom terminal only down plates.

The inductor relays E and F, when their coils are energized, have normally incomplete magnetic circuits which are successively completed by the inductor plates as the car approaches a floor at which a stop is to be made. These relays are so designed that energization of their operating coils will not produce operation of their contacts until the relay is brought opposite its inductor plate, thereby completing the relay magnetic circuit. Upon operation of the relay contacts (such as E1 or E2) they remain in operated condition until the relay operating coil is deenergized, even though the inductor relay moves away from the position opposite the inductor plate which completed its magnetic circuit. The plates should be so spaced in the hatchway as to provide desirable distances for slowdown and stopping of the cars at the floors. Other methods of controlling slowing down and stopping of the car may be used if so desired.

In the present system, which is given as an example of how the invention may be utilized, the various control circuits are so connected in accordance with our invention with a plurality of zone circuits that the system will operate with a low zone or lower group of floors including the first, second, third and fourth floors and a high zone or high group of floors including the fifth, sixth and seventh floors. Floor one may be considered as the parking floor. The division between the two zones of floors is determined by making certain wiring connections with the zone circuits as described later herein in connection with Fig. 5.

The cars and their control apparatus are provided for operation, under normal conditions, as a high call reversal system in which the cars stop for up calls on their up trips but automatically stop and reverse at the highest down call when there is no service required above that highest down call. If the car attendant desires, for any reason, to go above the highest down call while on an up trip he can do so by pressing a car call button, 6c, etc., for a floor above to cause the car to keep on up to such floor. However, at certain peak periods in down travel the system is adjusted or set to cause selected cars to serve down calls in the lower floors when they exceed a predetermined number.

In accordance with our invention, each car has a double throw zoning switch (19 in car A) by means of which it may be conditioned for operation as a low zone car or for operation as a high zone car.

When switch 19 is in its high-zone car position, its contacts 19a (Fig. 4) in the up stopping circuit are closed so that the car will answer up calls, and its contacts 19b (Fig. 6) are open to prevent operation of its limiting relay Z and its quota-adjusting relay Y. When switch 19 is in its low-zone car position, its contacts 19a are open to prevent the car from answering up floor calls and its contacts 19b are closed to permit operation of the relays Z and Y to make the car

5 a low zone car which will not normally go to the upper terminal; that is, it will answer only down calls in the low zone when they exceed a predetermined number but will go above that zone to answer a down call or down calls when the down calls in the low zone do not exceed that predetermined number. Thus the cars may be divided into two groups as desired so that the cars selected for the high zone group will run to the highest floor call of the upper zone before reversing and may stop for down floor calls in the lower zone on down trips and the cars selected for the low zone group may go to the upper zone but will not go to the upper zone and will answer only down calls, in the lower zone, when the conditions require this response. Obviously, low zone cars do not take on up passengers at the lower terminal and do not answer up calls and up passengers must 10 wait for high zone or through-trip cars.

15 A push-button switch 21 is provided in car A to permit the attendant to by-pass the calls ahead of his car when it is loaded or whenever the attendant desires to operate the car straight through. When switch 21 is pressed to by-pass calls, it opens its contacts 21a (Fig. 4) to prevent the car answering calls.

Apparatus in Fig. 2

20 Fig. 2 illustrates an enlarged view of the floor selector 16 of Fig. 1. In this figure, the various stationary contact segments are represented by rectangles and the contacting brushes by small circles. The brush carriage 17 is shown by dotted lines in the position it occupies when the associated car is stopped at the third floor.

25 The contact segments a2 to a7 on the floor selector are disposed to be successively engaged by the brush 30 to control the high car call relay 40 H and by the brush 31 for completing stop circuits set up by the call push-buttons in the car for up direction stops. The brush 30 should be long enough to bridge adjacent contact segments.

30 The contact segments b2 to b6 and the brush 32 are for connecting the circuits of the stop buttons 2U, etc., at the floor landings for up stops. The up contact segments c2 to c7 and the brush 33 are provided for connecting circuits for cancelling stop calls registered by the up hall call buttons 2U, etc. The up contact segments d1 to d7 and the brush 34 connect circuits for the high call relay to be described later. The contact segments e2 to e4 and the brush 40 connect circuits for limiting relays to be described later. 35 The down cancel contact segments f2, etc., and brush 41, the down floor call contact segments g2, etc., and brush 42, and the down car call contact segments h2, etc., and brush 43 are provided for connecting circuits for the down direction in the same manner as described for the up direction.

40 On the right-hand side of the floor selector, a series of switches 52 to 56 are illustrated as disposed to be operated by a cam 49 on the carriage 47 as it moves from its floor to floor position, for the purpose of controlling a high car call circuit.

Apparatus in Fig. 3

45 Referring particularly to Fig. 3 of the drawings, it will be observed that control circuits are shown on the left-hand side which are individual to car A. At the right-hand side, the circuits shown are individual to car B.

50 As shown, the motor 14 is provided with an armature 14A which is mechanically connected

to the shaft 13 for driving the sheave 11. The brake 15 is provided with a winding 20 which is energized on energization of the motor 14. The motor 14 includes the usual shunt-type main field winding 14F, which is connected for energization across the supply conductors L-1 and L+2. The armature 14A is connected for energization by a loop circuit 22 to a generator G which is provided with an armature GA.

In order to control the direction and magnitude of the voltage generated by the generator armature GA, a separately-excited main field winding GF is provided for the generator G. A field resistor R1 is included in the circuit of the field winding GF to provide speed control for the motor 14. The generator G is provided with suitable means such as a series field winding GS for correcting the speed regulation of motor 14.

The master switch CS located in car A is here shown connected to control the energization of the operating windings of an up reversing switch U and a down reversing switch D. The reversing switches U and D are provided with contact members for connecting the generator field winding GF to the conductors L-1 and L+1 in accordance with the direction in which it is desired to operate the car. When either the up or the down reversing switch U or D is energized, the car running relay M is also energized to condition certain circuits for operation. The common circuit of the reversing switches U and D and the running relay M includes the usual safety devices indicated diagrammatically at 23.

A high-speed relay V is provided for short-circuiting the resistor R1 disposed in series circuit relation with the generator field winding GF for applying the maximum voltage to that winding when the car is operating at normal high speed. This relay is controlled by the switches U and D on starting and by the slow-down inductor relay E when stopping.

An upper and a lower mechanical limit switch VTU and VTD, are provided for interrupting the circuit of the high-speed relay V when the car reaches a proper slow-down point in advance of the upper and lower terminals, respectively, and an upper and a lower stopping limit switch STU and STD, are provided for opening the circuits of the reversing switches U and D at the terminal limits, in accordance with the usual practice.

An up direction preference relay W and a down direction preference relay X are provided for controlling the direction of operation of the car and performing certain functions in connection therewith. The operating windings of these relays are controlled by a top limit switch 30T, a bottom limit switch 30B and the high-call reversal relays. Each of the limit switches 30T and 30B is arranged to be opened when car A arrives at the corresponding terminal, thereby interrupting the circuit of the direction preference relay W or X corresponding to the direction of operation of the car. Also when the high call reversal relays operate while the car is between terminals, the relays W and X are operated to reverse the direction switches. Hence the car attendant does not need to do anything except close or open the car switch CS and operate the car call buttons.

The energizing coils for the slowdown inductor switch E and the stopping inductor switch F, are illustrated in this figure as arranged to be energized on operation of the contacts S1 of a hall

call stopping relay S, the contacts T1 of a car button relay T or the contacts J1 of a high call reversing relay J. (The operating coils for relays S and T are illustrated in Fig. 4 and the coil for relay J is illustrated in Fig. 6 and will be described in connection therewith.)

An inductor holding relay G is provided for maintaining the inductor relays in energized condition during a decelerating or stopping operation.

A door relay DR is illustrated as controlled by a plurality of door safety contacts. The relay DR may be used for various safety circuits, and it is also used for assisting in the control of the high call reversing relay J shown in Fig. 6.

Apparatus in Fig. 4

The car buttons 2c, etc., described in connection with Fig. 1, are illustrated with their holding coils 2cc, etc., and circuits in the upper part of Fig. 4, in connection with the high car call relay H and the stopping relay T. The coils 2cc, etc., are energized when the car starts in either direction to hold in the car buttons 2c, 3c, etc., as they are operated, until the direction of the car is reversed, so that the temporary operation of a car button by the attendant will cause it to remain in operated condition until the car is reversed.

The high car call relay H is used to prevent relay J (Fig. 6) from reversing the car at the highest registered floor call when a stop call for a floor above is registered on the stop buttons in the car. It is connected by brush 30 to the row of contact segments a2, etc., on the floor selector 16, so that it will be energized whenever a stop call is registered on one of the stop buttons in car A for a floor above the car. The switches 52 to 56, inclusive, operated by the cam 49, are shown as disposed in the circuits of the car buttons to prevent energization of the relay H by operated stop buttons in car A for floors below that car.

The car stopping relay T is connected to the up brush 31 engaging the row of contact segments a2, etc., and to the down brush 43 engaging the row of contact segments h2, etc.; so that, when a call is registered on a car button and the car approaches the energized contact segment corresponding thereto, relay T will be energized to stop the car by energizing the inductor relays F and E.

The floor buttons 2U, 2D, etc., described in connection with Fig. 1 are shown with their circuits in the lower part of Fig. 4. Associated with each floor button is a call registering or storing relay by means of which the momentary pressing of the button will set up or register a stop call which will hold itself until it is answered by the stopping of a car at that floor for the direction of the registered call. The call registering relays are designated as 2DR to 7DR for the down direction and as 2UR, 3UR and 6UR for the up direction. For simplicity, the up direction registering relays and floor buttons for only the second, third and sixth floors are shown, as the up buttons and registering relays for the other floors will be readily understood.

The down call registering relays, when energized, close circuits to the row of contact segments g2, etc., and the up registering relays, when energized, close circuits to the row of contact segments b2, etc., on the floor selector so that the contact segment for a floor for which a call is registered is energized as long as the call exists.

A car stopping relay S is shown as connected to the up brush 32 engaging segments b2, etc., and the down brush 42 engaging segment g2, etc. When the car approaches a floor in a direction for which a call is registered, the corresponding brush engages the energized contact segment for that floor and that direction and thereby causes the relay S to be energized, which, in turn, energizes the inductor relays F and E of that car to effect the stopping of that car at that floor.

A cancellation coil is wound in opposition to each call registering coil and connected to the cancellation contact segments on the floor selector. The up cancellation coils are designated as 2URN, etc., connected to the up segments c2, etc., and the down cancellation coils as 2DRN, etc., connected to the down segments f2, etc. As the brush 33 moves over the segments c2, etc., and the brush 41 moves over the segments f2, etc., they energize the cancellation coil for any floor at which the car stops to answer a stop call.

Apparatus in Fig. 5

Fig. 5 embodies the high floor call relay K and the transfer relay TR together with the operating circuits therefor.

The high floor call relay K of car A is provided for controlling the operation of the high call reversing relay J for that car shown in Fig. 6, in accordance with the existence or non-existence of registered floor calls above it. In order to get a reversal of a car at a call, it is necessary to energize its relay K. This relay is connected to the supply conductor L+5, through either the normal call indicator circuit 50 for the high zone or through the low zone circuit conductor 51, depending upon whether relay TR is energized or deenergized. The circuits 50 and 51 are common to all the cars.

The circuit 50 includes back contacts of the up and the down call registering relays arranged in series relation according to the natural sequence of the floors and it is connected at floor points with the contact segments d1, d2, etc., through back contacts of the transfer relay TR. Consequently, when the relay TR is deenergized and car A is traveling on circuit 50, the relay K for car A will not be energized as long as a call exists at any floor above the floor of the contact segment on which the brush 34 rests, but as soon as the brush reaches a segment with no stored calls above it, a circuit for the relay is completed and it is energized.

The circuit 51 includes back contacts of only the down call registering relays for the floors included in the lower zone and they are arranged in series according to the natural sequence of the floors and the circuit is connected at floor points with the contact segments d1, d2, etc., through the front contacts of the relay TR. Therefore, when the quota relay Q and consequently the relay TR are energized, the relay K will not be energized as long as a down call exists at a floor in the low zone above the car but as soon as the car reaches the uppermost registered down call in the low zone, its relay K will be energized to effect its reversal.

The circuit 51 and the contacts therein provide means for dividing the floors into zones. The number of floors included in the low zone is determined by the number of lower floors having their hall call registering relay contacts included in the low zone circuit 51. The high zone includes the floors above the low zone. If it is desired to include more floors, in the low zone,

then back contacts of the down hall call registering relays for more floors should be included in circuit 51. Also, the contacts e in the circuits 21 should agree with the floors in the low zone to prevent the cars from getting quota actions after they leave the low zone. For instance, if it is desired to change the present system to a low zone of five floors, this can be effected simply by including back contacts of the down call registering device 5DR for the fifth floor in the low zone circuit 51 in a manner similar to the contacts 4DR2, connecting the contact segment d5 and Bd5 to the circuit 51 through front contacts of the transfer relays TR and BTR, and connecting a contact segment e5 in Fig. 6 to the circuit 21, so that the low zone cars will reverse in response to a predetermined number of down hall calls in the lower five floors instead of the lower four floors.

When a low zone car leaves the lower terminal on a trip, it starts up on the normal call indicator circuit 50. However, if a sufficient number of down calls are registered in the low zone to operate the quota device while a low zone car is running up therein, that device causes operation of the transfer relay TR of that car which, in turn, transfers that car from the normal circuit 50 to the low zone circuit 51, so that that low zone car will stop at the highest down call in the low zone, or at a higher floor in the low zone, depending upon the position of the car in the low zone, at the time the quota is filled.

The transfer relay TR is provided for transferring the relay K from control by the normal circuit 50 to control by the low zone circuit 51 when the car is a low zone car, the quota relay has been energized, and the car is moving upwardly in the low zone. The reversal of the car will be effected in the low zone in response to the filling 40 of the quota. Conversely, when the quota ceases to exist, the relay TR returns relay K to the control of the normal circuit 50. The relay TR effects this result because it is controlled by the up direction relay W (Fig. 3) and the relay Y (Fig. 6) which, in turn, is controlled by the quota relay Q (Fig. 6).

Apparatus in Fig. 6

Fig. 6 illustrates the circuits for the high call reversing relay J, the limiting relay Z, and the quota-adjusting relay Y for each of the cars, together with the quota relay Q which is common to all the cars.

The high call reversing relay J is provided for 55 so preparing the circuits of car A that it will reverse its direction of operation at the floor corresponding to the highest registered down call in the high zone when it is a high zone car and in the low zone when it is a low zone car. It stops 60 the car by closing its contacts J1 in the circuit of the inductor relays E and F (Fig. 3) and it then reverses the stopped car by opening its contacts J2 in the circuit of the up direction preference relay W (Fig. 3).

The quota relay Q is provided for totaling 65 the down calls in the low zone. It is common to all the cars and its energized operation is effected by a predetermined number of low zone down calls being in existence and a low zone car moving up in the low zone.

The energization of the quota relay is controlled by a plurality of branch circuits, each of which includes a quota resistor, such as R2, and which are controlled by contacts operated by the 70 down floor call relays, such as 4DR, in the low

zone, and by contacts operated by the low zone relay and the quota-adjusting relay Y. The quota relay and the resistors together with their connections are so designed that the relay will be responsive to a predetermined quota of registered down calls in the low zone.

For example, if car A is conditioned as a low zone car and is going up, its relay Z will be energized when the car leaves the first floor to close its contacts in the circuit for the quota relay Q. As long as no down call is registered in the low zone, the relay Q will not be energized. If only one down call in the low zone is registered, relay Q will still remain unoperated because sufficient current will not flow through the one resistor to actuate relay Q. As soon as two down calls in the low zone are registered, sufficient current will flow through the two resistors in parallel to actuate relay Q. The resistors and relay Q are normally so designed that at least two down calls in the low zone must exist before the relay will operate.

The limiting relay Z is provided to limit the floors at which a reversal can be made by a low zone car in response to operation of the quota relay Q, so that a low zone car can have its transfer relay operated only while it is moving up past floors in the low zone for which contact segments e are connected to the circuit 21. The relay Z is arranged for operation by the brush 40 engaging the contact segments e described in connection with Fig. 2.

As the fourth floor is, for the sake of simplicity in circuits, chosen as the top floor of the low zone in this illustration and description of the invention, it will be understood that it is difficult to satisfactorily illustrate the operation of segments e and the relay Z but it is believed that we have given sufficient information to enable any one skilled in the elevator art to easily construct and install a satisfactory control circuit embodying these features.

The quota-adjusting relay Y is provided for energizing the transfer relay TR upon operation of the quota relay Q and for so controlling the circuit of the relay Q as to deenergize that relay when car A is given the quota of down floor calls registered in the low zone. The relay Y is prepared for action only when the car is conditioned for operation as a low zone car by the closing of contacts 19b and after that it is energized when the quota relay is energized. When energized, relay Y closes its self-holding circuit and remains energized until car A reverses. A switch 26 operable by a cam when the car arrives at the parking floor is provided to prevent operation of the relays Z and Y and hence the transfer relay TR until the car leaves the parking floor.

It is believed that the invention may be better understood by assuming an operation of the apparatus and circuits described.

Operation as high zone car

The first operation assumed will be that of cars A and B as normal high call reversal cars standing at the lower terminal with the doors (not shown) closed and with no stop calls registered. Under these conditions, the door relay DR, the up direction preference relay W and the high floor call relay K of car A are in energized condition. The door relay DR is energized because all the doors are closed, thus completing the circuit: L+1, door contacts, DR, L-1. The relay W is energized because the bottom

terminal switch 30B is open thus deenergizing relay X which closes its back contact X2. The circuit for relay W extends: L+1, D6, X2, J2, W, 30T, L-1. The relay K is energized because no calls are registered to affect the circuit 50.

Car A is conditioned as a high zone car because its switch 19 has its contacts 19a closed and its contacts 19b open. Car A will now operate on circuit 50 (Fig. 5) but not on circuit 51. With the door closed, the car attendant in car A closes the car switch CS temporarily to start the car upwardly by energizing the up direction switch U and the car running relay M through the following circuit:

15 L+1, CS, CS1, W1, F1, STU, U, M, 23, L-1

The energized relay M closes its contacts M1, M2, and M3 and opens its contacts M4 to prepare the control system of car A for operation.

20 The energized up direction switch U closes its contacts U1, U2, U3, U4 and U5 and opens its contacts U6 to start the car upwardly. The closing of contacts U1 energizes the brake coil to release the brake 15 (Fig. 3). The closing of contacts U2 and U3 energizes the field winding GF of the generator G by the circuit L+1, U2, GF, U3, R1, L-1. The energization of the field winding GF causes the motor to supply energy to the hoisting motor 14 for operating the drum 11 to move car A upwardly.

30 The closing of the contacts U4 energizes the high speed relay V by the circuit L+1, U4, VTU, E1, V, L-1. The energized relay V closes its contacts V1 thereby shorting the resistor R1 in the circuit of the generator field winding GF, thus increasing the energization of the field winding GF to cause the motor 14 to move the car upwardly at its normal high speed.

It will be assumed now before car A reaches 40 the second floor that a waiting down passenger at the sixth floor operates the down call button 6D to register a down stop call for that floor. The operation of button 6D energizes the relay 6DR by the circuit L+3, 6D, 6DR, 60, 61,

45 L-3. The energized relay 6DR closes its contacts 6DR1 in its self-holding circuit. It also supplies energy to the contact segments g6 and Bg6 to stop the next approaching car which is conditioned to serve it. The operated relay 6DR also opens its contacts 6DR5 in the high call circuit 50 thereby deenergizing the high floor call relay K. The deenergized relay K opens its contacts K1 in the circuit of the high call reversal relay J.

55 It will be assumed that car A moves upwardly in the hatchway on its up trip with no call registered above it except the down call at the sixth floor. As it approaches the sixth floor, its brush 34 engages the energized contact segment d6 and thereby energizes the high floor call relay K by the circuit:

60 L+5, 7DR3, 6UR2, d6, 34, K, L-5

The energized relay K closes its contacts K1 and thereby energizes the high call reversing relay J by the circuit:

65 L+7, J, H1, K1, W8, L-7

70 The energized relay J closes its contacts J1 (Fig. 3) thereby energizing the slow down inductor relay E and the inductor holding relay G to effect the stopping of the car at the sixth floor. The relay G, in turn, closes its contacts G1 to energize the stopping relay F.

75 As car A approaches closer to the sixth floor

its inductor relay E comes opposite the up plate UEP for that floor and its contacts E1 are opened, thus deenergizing the high speed relay V. The relay V opens its contacts V1 to insert the resistor R1 in the circuit of the generator field winding GF thereby decreasing the speed of the hoisting motor 14 and thus slowing down the car. As the car approaches still closer to the sixth floor, its stopping relay F comes opposite the up stopping plate UFP for that floor which opens its contacts F1, thereby deenergizing the car running relay M and the up direction switch U. The switch U opens its contacts U1 in the brake circuit and opens its contacts U2 and U3 in the circuit of the generator field winding GF, thus stopping the car and applying the brake to hold it at the sixth floor.

At the same time the contacts J2 of the energized high call reversing relay J are open in one of the parallel circuits of the up direction preference relay W. Therefore, when the contacts M2 of the car running relay M are opened for the sixth floor stop, they open the other parallel circuit for the relay W and thus deenergize it. The deenergized relay W thereupon closes its back contacts W2 which energizes the down preference relay X by the circuit L+1, U6, W2, X, 30B, L-1. The deenergized relay W also opens its contacts W1 in the circuit of the up direction switch U and the down preference relay X closes its contacts X1 in the circuit of the down direction switch D. This prepares the car for down operation and when the attendant closes the starting switch CS, the car will start downwardly.

Assuming now that the attendant closes the car switch CS he thereby energizes the down direction switch D and the car running relay M by the circuit L+1, CS, CS1, X1, F2, STD, D, M, 23, L-1. The energized switch D and the relay M cause the car to move downwardly to the first floor where the arrival of the car opens the lower limit switch STD to deenergize the down direction switch D.

Also, as the car reaches the first floor, it opens its bottom terminal switch 30B to deenergize the down preference relay X which, in turn, closes its back contacts X2 to energize the up direction preference relay W to condition the car for up direction operation.

It is seen by the foregoing description how a normal car operates on an up trip to reverse itself at the highest down call when there are no up calls above it to be answered.

Operation of stopping and reversing low zone car at highest down call in low zone

It will be assumed now, in practicing our invention, that the cars A and B are to be conditioned for operation as low zone cars. This is done by moving the switch 19 in car A and the switch B19 in car B to the right. The movement of the switch 19 opens its contacts 19a and closes its contacts 19b. The opening of the contacts 19a disconnects the up stop brush 32 from the stopping relay S so that car A will not respond to any registered up call stops. The closing of the contacts 19b prepares the limit relay Z, the limit circuit 21 and the quota-adjusting relay Y for operation. The control apparatus of car A is now conditioned to operate it as a low zone car. The opening of the contacts B19a and the closing of the contacts B19b condition the circuits of car B to cause it to operate as a low zone car. Both cars now are ready for operation on circuits 50

and 51. As long as the quota relay is not operated, the cars operate on circuit 50 but when the quota relay Q is operated, it transfers the first up moving low zone car from circuit 50 to circuit 51.

It will be assumed now that cars A and B are standing at the lower terminal ready for operation as low zone cars. Under these circumstances, with the doors closed, the door relay DR, the up direction relay W and the high floor call relay K of car A are energized. The same relays for car B are also energized for operation.

It will also be assumed that a waiting down passenger at the second floor operates the down call button 2D at the second floor, thereby energizing the down call registering relay 2DR by the circuit L+3, 2D, 2DR, 60, 61, L-3. The energized relay 2DR opens its contacts 2DR3 in the circuit 50 and its contacts 2DR2 in the circuit 51 and closes its contacts 2DR4 in the circuit of the quota relay Q. The opening of contacts 2DR3 deenergizes the high floor call relay K. The energized relay 2DR also closes its contacts 2DR1 to establish a self holding circuit and energize the stopping segments g2 and Bg2 to stop the next car conditioned to answer it.

It will be assumed also that a waiting down passenger at the sixth floor presses the down call button 6D at that floor and thereby energizes the down call storing relay 6DR as previously described to energize its stopping segments g3 and Bg6 to stop the next car conditioned to serve it.

It will be assumed further that a waiting down passenger at the third floor presses the down button 3D for that floor, thereby energizing the down call registering relay 3DR for the third floor which in turn closes its self holding contacts 3DR1 and energizes the contact segments g3 and Bg3 to stop the next approaching car conditioned to serve it. The energized relay 3DR also opens its contacts 3DR3 in the circuit 50 and 3DR2 in the circuit 51 and closes its contacts 3DR4 in the circuit of the quota relay Q.

It will be assumed now that the attendant in car A closes temporarily its switch CS to start the car upwardly. This energizes the up direction switch U and the car running relay M to start car A upwardly in the manner previously described.

As car A leaves the first floor, it closes its cam switch 26, thereby energizing the limit relay Z by the circuit L+1, 21, e2, 40, Z, W10, 19b, 26, L-1. The operation of the relay Z closes its contacts Z1, thereby energizing the quota relay Q because the circuit of that relay has been prepared for operation by the registration of down calls at the second and third floors in the low zone. This quota of two calls will cause the car to stop and reverse at the third floor in the low zone. It will be recalled that the quota relay is adjusted to operate when two down calls are registered in the low zone with a low zone car going up in that zone, but of course it may be designed for operation by any other total of registered calls.

The circuit for the quota relay extends through the parallel resistors R3 and R2 because the contacts 3DR4 and 2DR4 in the quota circuit are closed by reason of the down stored calls at the third floor and the second floor and thence through the coil Q and the contacts Y3, BY3 and Z1 to the supply conductor L-7.

The energized relay Q closes its contacts Q1 and Q2 in the circuits of the quota-adjusting relays Y and BY for the cars A and B. Relay BY

is not energized because its switch B26 is open. The circuit for relay Y extends L+7, Q1, Y, Z2, W10, 19b, 28, L-7. The energized relay Y closes its contacts Y1 and Y4 and opens its contacts Y3.

The closing of the contacts Y4 establishes a self-holding circuit for the relay Y while the opening of its contacts Y3 deenergizes the quota relay Q and restores it to its normal condition.

The closing of the contacts Y1 energizes the transfer relay TR by the circuit L+5, Y1, W1, TR, L-5. The energized relay TR closes its self-holding contacts TR13 and closes its contacts TR5, TR7, TR9 and TR11 leading to the low zone circuit 51 and opens its back contacts TR6, TR8, TR10 and TR12 leading to the normal call circuit 50 (Fig. 5). This operation transfers the control of the high floor call relay K from the circuit 50 to the circuit 51 so that it will cause the low zone car A, which now has its quota of down calls, to stop and reverse at the third floor in the low zone.

As car A passes the second floor, the segment d2 is dead because of the open contacts 3DR2 above it in circuit 51. However, as car A continues its approach to the third floor, its brush 34 engages the energized contact segment d3 connected to the upper energized section of circuit 51 and thereby establishes a circuit for energizing the relay K as follows:

L+5, 51, 4DR2, TR1, d3, 34, K, L-5

Thus, as the energized relay K closes its contacts K1 (Fig. 6) it energizes the high call reversing relay J by the circuit previously described. Thereupon the relay J closes its self-holding contacts J3 and J4 and also closes its contacts J1 to energize the slow down inductor relay E and the holding relay G which, in turn, closes its contacts G1 to energize the stopping inductor relay F. The relay J also opens its contacts J2 in the circuit of the relay W. The inductor relays are operated as the car passes the up slow down plate UEP and stopping plate UFP for the third floor as previously described in connection with the sixth floor stop, thereby deenergizing the up relay U and the running relay M and thus stopping car A at the third floor in response to the operation of the reversing relay J.

Car A is now reversed at the third floor because the contacts J2 and M2 are opened in the parallel circuits leading to relay W, thus deenergizing relay W which in turn energizes relay X, as previously described.

As car A is stopped and reversed at the third floor in answer to the down call thereat, its deenergized relay M and its energized relay X complete the following circuit for energizing the coil 3DRN to cancel that down call:

L+3, 3DR1, 3DRN, f3, 41, X6, M4, L-3

The energized coil 3DRN restores the call registering relay 3DR to its normal condition, thereby opening its front contacts and closing its back contacts. Thus the opening of contacts 3DR4 renders the resistor R3 ineffective in the circuit of the quota relay Q and at least one additional down call in the low zone must be registered again to operate the quota relay to stop another car.

The deenergized up direction relay W also opens its contacts W1 and W10 thereby deenergizing the transfer relay TR, the limiting relay Z and the adjusting relay Y of car A. The deenergized relay Y closes its contacts Y3, thereby restoring the quota relay Q to normal condition

ready for another operation when another low zone car is moving up in the low zone and a quota of two down calls exists. When the down call stop at that floor is completed, the car attendant closes the switch CS temporarily, the car starts downwardly and stops at the second floor for the call thereat and then moves on down to the lower floor where the operation of its limit switches restores it to its normal condition for up operation as a low zone car.

By the foregoing operation, it is seen that a low zone car will stop and reverse at the highest down call in the low zone when a predetermined number of down calls are registered therein before it passes all of them.

Low zone car staying in low zone

It will be assumed now that cars A and B are low zone cars and are standing at the lower landing. It will also be assumed that a waiting down passenger at the third floor presses the down button 3D at that floor thereby energizing the down call registering relay 3DR for the third floor which, in turn, closes its self-holding contacts 3DR1 and energizes the contact segments g3 and Bg3 to stop the next approaching car conditioned to serve it. The energized relay 3DR also opens its contacts 3DR2 in the circuit 51 and its contacts 3DR3 in the circuit 50 and closes its contacts 3DR4 in the circuit of the quota relay Q.

It will be assumed that a waiting down passenger at the sixth floor presses the down call button 6D at that floor and thereby energizes the down call storing relay 6DR as previously described to energize its stopping segments g6 and Bg6 to stop the next car conditioned to serve it. The energized relay 6DR also opens its contacts 6DR5 in the normal circuit 50.

It will be assumed now that the attendant in car A temporarily closes its switch CS and thereby starts the car upwardly by energizing the up direction switch U and the car running relay M as previously described.

As car A leaves the first floor, it closes its cam switch 26. As previously described, this effects energization of the limit relay Z when the brush 40 engages the contact segment e2. The energized relay Z closes its contacts Z1 in the circuit of the quota relay Q but inasmuch as only one down call has been registered in the low zone, the quota relay remains unenergized.

It will be assumed now that as the car passes the third floor a waiting down passenger at the second floor presses the down button 2D at that floor, thereby energizing the down call registering relay 2DR for the second floor, which in turn closes its self-holding contacts 2DR1 and energizes the contact segments g2 and Bg2 to stop the next approaching car conditioned to serve it. The energized relay 2DR also opens its contacts 2DR2 in the circuit 51 and its contacts 2DR3 in the circuit 50 and closes its contacts 2DR4 in the circuit of the quota relay Q. Hence with the down call at the third floor and the down call at the second floor, the quota of two down calls is created in the low zone while car A is passing the higher one at the third floor. Although it is too late to stop car A at the third floor, it will remain in the low zone and will be stopped and reversed at the next floor to answer the down calls at the third and second floors.

The filling of the quota just as car A passes the third floor energizes the quota relay by the circuit from L+7, in parallel through contacts

3DR4 and 2DR4, in parallel through resistors R3 and R2, and thence through Q, Y3, BY3, Z1, L-1.

The energized relay Q closes its contacts Q1 and Q2 in the circuits of the quota adjusting relays Y and BY for the cars A and B and relay Y is energized by the circuit previously described.

The energized relay Y closes its contacts Y1 and Y4 and opens its contacts Y3. The closing of the contacts Y4 establishes a self-holding circuit for the relay Y and the opening of its contacts Y3 restores the quota relay Q to its normal condition.

The closing of the contacts Y1 energizes the transfer relay TR by the circuit previously described. The energized relay TR closes its self-holding contacts TR13 and its contacts TR5, TR1, TR9 and TR11 leading to the circuit 51 and opens its contacts TR6, TR8, TR10 and TR12 between the d contacts and the normal circuit 50. This operation transfers the control of the high floor call relay K of car A from the circuit 50 to the circuit 51, so that the circuit 51 will cause car A to be stopped and reversed in the low zone because the quota has been filled and the quota relay Q has been operated.

As car A continues its approach to the fourth floor, its brush 34 engages the contact segment d4 connected to the upper energized portion of circuit 51 and thereby energizes the relay K now transferred to this circuit, as previously described.

As the energized relay K closes its contacts K1, it energizes the high call reversing relay J by the circuit previously described. Thereupon the relay J closes its contacts J1 to energize the slow down inductor relay E and the holding relay G which, in turn, energizes the stopping inductor relay F. The inductor relays operate as the car passes the up slow down plate UEP and the stopping plate UFP for the fourth floor, as previously described in connection with the sixth floor stop, thereby stopping car A at the fourth floor in response to the operation of the quota device.

The energized relay J also opens its contacts J2 in the parallel circuit for the relay W, thereby reversing the car as previously described. When the car stops, the attendant closes the car switch CS temporarily to restart the car. As the car has been reversed, it starts downwardly and is stopped at the third floor by the down call registered thereat. As soon as the waiting passenger at the third floor enters the car, the attendant closes the switch CS temporarily and the car starts downwardly, stopping at the second floor for the down call thereat and then going down to the lower floor where the operation of its limit switches restores it to normal condition for the next up trip.

It will also be observed that, although a down call was registered at the sixth floor in the upper zone, that registered call did not affect the reversal of the car in the low zone. The down call at the sixth floor did not affect the operation because the quota relay operated the relay Y which operated the transfer relay TR to transfer car A from the normal circuit 50 (which included the sixth floor call relay contacts 6DR5) to the low zone circuit 51 which did not include any contacts of the sixth floor call relay 6DR.

Operation of low zone car into upper zone

In order to illustrate how a low zone car may go out of the lower zone into the upper zone

and answer down calls in the upper zone, the following assumed operation is given.

It will be assumed that down calls are registered at the sixth floor, the fifth floor and the second floor.

The operation of the button 6D for the down call at the sixth floor energizes the relay 6DR by the circuit previously described. The energized relay 6DR closes its contacts 6DR1 to complete its self-holding circuit while it energizes contact segment g6 and also opens its contacts 6DR5 in normal circuit 50.

The operation of the button 5D for the down call at the fifth floor energizes the relay 5DR by the circuit L+3, 5D, 5DR, 60, 61, L-3. The energized relay 5DR closes its self-holding contacts 5DR1 and energizes the contact segments g5 and Eg5 and opens its contacts 5DR4 in the normal circuit 50.

The pressing of the down button 2D at the second floor energizes the call registering relay 2DR as previously described for energizing the contact segment g2 and for opening the circuits 50 and 51 and for closing one circuit through resistor R2 to the quota relay Q.

It will be assumed now that both cars A and B are at the lower terminal and that they have been conditioned by operation of their switches 19 and B19 to operate as low zone cars. With car A at the first floor, its up direction preference relay W is energized and, assuming that its door is closed and that the attendant closes the car switch CS, then the car starts on an up trip as previously described. Inasmuch as only one down call (second floor) is now registered in the low zone, the quota relay Q is not operated.

As car A passes out of the low zone by leaving the fourth floor and approaching the fifth floor, its brush 40 leaves the contact segment e4, thus deenergizing the relay Z and preventing car A from being given a quota after it runs above the low zone.

As car A moves on upwardly, its brush 34 engages the energized contact segment d6 and thereby energizes relay K to cause the stopping and reversal of car A at the highest down call in the upper zone which is at the sixth floor, there being a down call at the fifth floor which the low zone car did not now answer because the contacts 6DR5 were open in the circuit 50. The circuit for the high floor call relay K extends:

L+5, 1DR3, 6UR2, d6, 34, K, L-5

The energized relay K closes its contacts K1 (Fig. 6) and thereby energizes the high call reversing relay J of car A by the circuit previously described. The relay J, in turn, closes its contacts J1 in the circuit of the slowdown inductor relay E and the inductor holding relay G, thereby energizing those relays to effect the slowing down and stopping of car A at the sixth floor, as previously described. The energized relay J also opens its contacts J2, and, inasmuch as the car running relay M has opened its contacts M2 in

the parallel circuit for up direction preference relay W, that relay is deenergized and thereupon closes its back contacts W2 in the circuit for the down direction preference relay X. The deenergized relay W opens its contacts W1 in the circuit of the up direction switch U, and the down direction preference relay X closes its contacts X1 in the circuit of the down direction switch D (Fig. 3) so that the next closing operation of the

car switch CS will cause car A to move downwardly.

It will be assumed now that the attendant temporarily closes the car switch CS and that car A moves downwardly. As car A approaches the fifth floor, its brush 42 engages the energized down contact segment g5 for the fifth floor and thereby completes a circuit for energizing the stopping relay S which closes its contacts S1 to energize the inductor relays to effect the stopping of the car, as previously described. Car A is now stopped at the fifth floor and takes on the waiting passengers.

It will be assumed now that car A has taken on all the passengers it can carry and that the car attendant presses the by-pass button 27 thereby opening its contacts 27a to prevent energization of the stopping relay S. As the car attendant closes the car switch CS temporarily, car A starts down to the lower terminal and by-passes the down call at the second floor, because its stopping relay S has been rendered ineffective by the operation of the by-pass button 27.

By the operation just assumed, it is seen that a low zone car which passes out of the low zone because of the small number of down calls registered in that zone at that time, will be stopped and reversed at the highest down call in the upper zone.

Any low zone car leaving the low zone without quota will operate on the high call reversal circuit 50, because its transfer relay TR is not energized. However, if the highest registered call above it is an up call, the low zone car will not stop there but will go one floor beyond it and then stop and reverse, answering any down calls it meets on its down operation. It will not answer the up call while moving up, because its up brush 32 is disconnected by the open contacts 19a of the zone selecting switch 19.

It also will be apparent from the foregoing description and assumed operations that we have provided a flexible control system whereby part of the cars in a bank of elevators can be operated as high call reversal cars and the other part of the cars can be operated as low zone cars, but that the low zone cars will leave the low zone and move into the high zone if they do not have at least a predetermined number of down calls to answer in the low zone. This is a novel result as it makes the system very flexible and does not limit the cars to only certain floors for operation but causes them to so act normally that the one group serves the upper floors and the other group serves the lower floors but that either group may help out the other group and not be limited only to one zone of operation.

Although we have illustrated and described only one specific embodiment of our invention, it is to be understood that modifications thereof and changes therein may be made without departing from the spirit and scope of the invention.

We claim as our invention:

1. In an elevator system, a plurality of cars for serving a plurality of floors, means dividing the floors into zones including a low zone and a high zone, means for conditioning any selected car as a low zone car, an operating means for each car, an up call device and a down call device at each floor and common to all the cars, for causing the operating means of the cars to stop the cars thereat when they are in condition to make such stops, and means responsive to a predetermined number of down call devices in the low zone

being in operated condition for controlling the zone dividing means to cause the operating means of an up moving low zone car in the low zone to stop it and reverse it at the highest operated down call device in the low zone.

2. In an elevator system, a plurality of cars for serving a plurality of floors, means dividing the floors into zones including a low zone and a high zone, means for conditioning any selected car as a low zone car, an operating means for each car, an up call device and a down call device at each floor and common to all the cars, for causing the operating means of the cars to stop the cars thereat when they are in condition to make such stops, a quota device common to all the cars, a plurality of circuits responsive to a predetermined number of down call devices being in operated condition for operating the quota device, and means responsive to operation of the quota device for controlling the zone dividing means to cause the operating means of an up moving low zone car in the low zone to stop it and reverse it at the highest operated down call device in the low zone.

15 3. In an elevator system comprising a car serving a plurality of floors divided into zones including a low zone and a high zone, an operating means for the car, an up call device and a down call device at each floor for causing the operating means of the car to stop it thereat when it is in condition to make such stop, a normal call-above circuit for causing the car to stop at the highest call, a special call-above circuit for causing the car to stop at the highest call in the low zone, 20 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone, 25 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone, 30 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone, 35 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone, 40 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone, 45 means responsive to operation of the call devices for controlling the normal call circuit and the special call circuit, a quota device, means responsive to a predetermined number of down call devices in the low zone being in operated condition for causing the operating means of the car to stop it thereat when it is in condition to make such stop, a normal call-above circuit for causing the car to stop at the highest call, a special call-above circuit for causing the car to stop at the highest call in the low zone.

4. In an elevator system, a plurality of cars for serving a plurality of floors, means for dividing the floors into groups including an upper group and a lower group, a call device for each direction of operation for each floor operable to register stop calls for the cars at that floor, means for operating the cars, a reversing means for each car operable on up motion of that car for causing it to normally stop at the highest floor for which a down call device is in operated condition when

55 there is no other call above it, and means responsive to a predetermined number of down call devices for floors in said lower group being in operated condition for controlling the dividing means to cause the reversing means of one of the cars on its up motion in the lower group to stop it at the highest floor in said lower group for which a down call device is in operated condition and to cause further movement of said car to be in the down direction.

60 5. An elevator system comprising a plurality of cars for serving a plurality of floors including an upper terminal floor, a lower terminal floor and intermediate floors; an operating means for each car, an up call device and a down call device for each of the floors intermediate the terminal floors for causing the operating means of the cars to stop them thereat when they are in condition to make such stops, means for causing

the up moving cars to stop and reverse their direction of operation at the highest operated call device when it is a down call device, means for dividing the floors into zone groups including a low zone group and a high zone group, means for conditioning any selected car or cars for special service for the low zone group of floors, and a quota means responsive to a predetermined number of down call devices in the low zone group of floors being in operated condition for controlling the reversing means to cause the operating means of an up moving low zone car in the low zone to stop and reverse it in that zone.

6. An elevator system comprising a plurality of cars for serving a plurality of floors intermediate an upper terminal floor and a lower terminal floor, an operating means for each car, an up call device and a down call device for each intermediate floor for causing the operating means of the cars to stop them thereat when they are in condition to make such stops, means for causing the up moving cars to stop and reverse their direction of operation at the highest operated call device when it is a down call device, means for dividing the floors into groups including a low zone group and a high zone group, means for conditioning any selected car or cars for special service in the low zone group of floors, a quota means common to all the cars and responsive to a predetermined number of down call devices in the low zone group of floors being in operated condition for controlling the reversing means to cause the operating means of an up moving low zone car in the low zone to stop and reverse it at the highest operated down call device in the low zone group of floors, and means responsive to operation of the stopping and reversing means of said up moving car for returning the quota means to normal condition and requiring the operation of an additional down call device in the low zone to cause stopping and reversal of the next up moving low zone car which enters the low zone after the quota means is returned to normal condition.

7. An elevator control system for a plurality of cars for serving a plurality of floors, comprising means for connecting the control system to divide the floors into groups including an upper group and a lower group, a means for operating each car through all floors, an up call device and a down call device at each floor for causing the operating means of the cars to stop the cars thereat when they are in condition to make such stops, and means responsive to a predetermined number of down call devices for the lower group of floors being in operated condition for controlling the zone dividing means to cause an up moving car in the lower group to remain in that group of floors.

8. An elevator system comprising a car serving a plurality of floors divided into zones including a low zone and a high zone, an operating means for the car, a call device at each floor for causing the operating means of the car to stop it thereat when it is in condition to make such stop, a normal call-above circuit for both zones, a special call-above circuit for the low zone, means responsive to operation of the call devices for controlling the normal call circuit and the special call circuit, car reversing means responsive to operation of the normal circuit for stopping and reversing the car at the highest call, and a quota device responsive to a predetermined number of call devices in the low zone being in operated condition for conditioning the call above circuits and

the reversing means to cause the car while in the low zone to stop and reverse in that zone.

9. An elevator system comprising a car serving a plurality of floors divided into zones including a low zone and a high zone, an operating means for the car, a call device at each floor for causing the operating means of the car to stop it thereat when it is in condition to make such stop, a normal call-above circuit for both zones, a special call-above circuit for the low zone, means responsive to operation of the call devices for controlling the normal call circuit and the special call circuit, car reversing means responsive to operation of the normal circuit for stopping and reversing the car at the highest call, a quota device responsive to a predetermined number of call devices in the low zone being in operated condition for conditioning the call above circuits and the reversing means to cause the car while in the low zone to stop and reverse at the highest call in that zone, means responsive to the stopping of the car at a call in the low zone for cancelling the call thereat, and means responsive to the cancellation of the call for deenergizing the quota device.
10. An elevator system comprising a plurality of cars serving a plurality of floors divided into zones including a low zone and a high zone, an operating means for each car, an up call device and a down call device at each floor for causing the operating means of any car to stop it thereat when it is in condition to make such stop, call-above circuits for the zones, means responsive to operation of the call devices for controlling the call-above circuits, car reversing means for each car responsive to operation of the circuits for stopping and reversing that car at the highest call, a quota device common to all the cars, means responsive to a predetermined number of down call devices in the low zone being in operated condition for operating the quota device, and means responsive to operation of the quota device for conditioning the call-above circuits and the reversing means of an up moving car in the low zone to stop and reverse in that zone.

11. An elevator system comprising a plurality of cars serving a plurality of floors divided into zones including a low zone and a high zone, an operating means for each car, an up call device and a down call device at each floor for causing the operating means of any car to stop it thereat when it is in condition to make such stop, call-above circuits for the zones, means responsive to operation of the call devices for controlling the call-above circuits, car reversing means for each car responsive to operation of the circuits for stopping and reversing that car at the highest call, a quota device common to all the cars, means responsive to a predetermined number of down call devices in the low zone being in operated condition for operating the quota device, means responsive to operation of the quota device for conditioning the call above circuits and the reversing means of an up moving car in the low zone to stop and reverse it to answer the highest operated down call device in that zone, and means responsive to that car answering the highest operated call device in the low zone for rendering the quota device ineffective to stop the next car which enters the low zone after said highest call device is answered until at least one additional down call device in the low zone is operated.

12. An elevator system comprising a plurality of cars serving a plurality of floors divided into zones including a low zone and a high zone, an

operating means for each car, an up call device and a down call device at each floor for causing the operating means of any car to stop it thereat when it is in condition to make such stop, call-above circuits for the zones, means responsive to operation of the call devices for controlling the call-above circuits, car reversing means for each car responsive to operation of the circuits for stopping and reversing that car at the highest call, a quota device common to all the cars, means responsive to a predetermined number of down call devices in the low zone being in operated condition for operating the quota device, means responsive to operation of the quota device for conditioning the call-above circuits and the reversing means of an up moving car in the low zone to stop and reverse it to answer the highest operated down call device in that zone, means responsive to that car answering the highest operated call device in the low zone for returning that call device to its unoperated condition, and means responsive to the return of that call device to its unoperated condition for returning the quota device to its unoperated condition to require the operation of at least one additional down call device in the low zone for again operating the quota device to stop a second car.

13. An elevator system comprising a plurality of cars serving a plurality of floors divided into zones including a low zone and a high zone, an operating means for each car, an up call device and a down call device at each floor for causing the operating means of any car to stop it thereat when it is in condition to make such stop, call-above circuits for the zones, means responsive to operation of the call devices for controlling the call-above circuits, car reversing means for each car responsive to operation of the circuits for

stopping and reversing that car at the highest call, a transfer means for each car, a quota device common to all the cars, means responsive to a predetermined number of down call devices in the low zone being in operated condition for operating the quota device, means responsive to operation of the quota device for controlling the reversing means and the transfer means of an up moving car in the low zone to cause the stopping and reversing of that car to answer the highest operated down call device in that zone.

14. In an elevator control system for a plurality of cars for serving a plurality of floors, means for dividing the floors into a low zone group and a high zone group, means for selectively conditioning the cars to operate as low zone cars or as high zone cars, an operating means for each car, control means at each floor for causing the operating means of the cars to stop them thereat when they are in condition to make such stops, a single normal call-above circuit-common to the cars and controlled by the control means at each floor, a single low zone call-above circuit common to the cars, and controlled by the control means at the floors in the low zone group, a high call reversal means for each car normally connected for control by the normal call-above circuit, and means responsive to a predetermined number of operated control means at floors in the low zone group for transferring the high call reversal means of a low zone car moving upwardly in the low zone from control by the normal call-above circuit to control by the low zone call-above circuit to effect reversal of that car in the low zone instead of at the highest operated control means in the system.
